METHODS FOR MAKING BANDS FROM YARN OR THE LIKE

Madison H. Briscoe, Athens, Ga., assignor, by mesne assignments, to Circular Banding Company, Inc., Athens, Ga., a corporation of Georgia

Application January 18, 1956, Serial No. 559,954

2 Claims. (Cl. 57—158)

This invention relates to methods and apparatus for making bands from yarn or the like and more particularly to such methods and apparatus whereby a continuous length of elastic yarn, nylon covered or cotton covered rubber yarn for example, may be formed into a hook type band or round belt.

Hook type bands and round belts made from elastic yarn or the like have utility for power transmitting purposes, particularly high speed power transmitting purposes. For such purposes they should be elastic and flexible yet strong and should have a smooth and firm outer surface in order to minimize friction which, of course, can be especially troublesome at high speeds. By employing methods and apparatus in accordance with the teaching of the present invention, it is possible to make such bands, and the term band is to be understood as including the term belt, relatively rapidly and economically. Furthermore, the completed band is structurally in equilibrium and presents a smooth and firm outer surface.

Accordingly, it is an object of the present invention to provide new and improved methods of making bands which are useful for power transmitting purposes from yarn or the like.

It is another object of the present invention to provide such methods wherein the completed band is made from a continuous length of unstretched elastic yarn or the like twisted in such a manner that the completed band is structurally in equilibrium, presents a smooth and firm outer surface, and has a controlled maximum amount of elasticity.

It is a further object of the present invention to provide such methods whereby the amount of twist to be imparted to the yarn or the like may be readily controlled.

It is still another object of the present invention to provide a method of making an elastic band which is adapted to be completed into an endless band.

It is a still further object of the present invention to provide new and improved apparatus for making elastic bands useful for power transmitting purposes from yarn or the like.

Briefly described, a preferred method according to the teaching of the present invention includes an initial step of winding or otherwise forming a length of unstretched yarn, elastic nylon or cotton yarn for example, into two groups of strands having a common apex. The strand groups are so disposed that they define an acute angle and are preferably in the form of an elongated V. Preparatory to twisting the strand groups as next described, the two ends of the length of yarn are buried among the strands of one strand group adjacent one of the open V ends.

The two open V ends are then twisted in the same direction and preferably at the same rate of twisting while the apex of the V is held against rotation. This twisting is stopped before kinking occurs and results in two twisted strand groups, the ends of the yarn which were placed in one of the strand groups prior to the twisting now being

2

locked securely within the twisted strand group. After the twisting of the ends is stopped, the ends are still held but the apex is released to permit the twisted strand groups to twist together upon themselves into an elongated band. Following this last mentioned twisting action, the two formerly open ends of the V are brought together, the strand groups continuing to twist together upon themselves as this is done, and secured together by a suitable means such as a band hook.

10 A preferred apparatus for carrying out the method just described includes two adjacent shafts each having a hook projecting from a corresponding end. The shafts are supported so that they, and the hooks, may be rotated simultaneously in the same direction. One of the shafts 15 has a clip mounted thereon for securing one free end of a length of yarn preparatory to threading the yarn about the hooks. A tail hook is positioned away from the two adjacent shaft hooks along a center line extending between them so that when a length of unstretched yarn is 20 threaded from one shaft hook to the tail hook and then back to the other shaft hook it will be disposed in an elongated V. The tail hook is preferably supported by a free turning shaft. However, pin means are provided for insertion between the two groups of strands extending 25 from the tail hook so that when the strand groups are twisted by the shaft hooks, the tail hook may be kept from rotating thereby permitting the two strand groups to be twisted by the shaft hooks. Then, when the shaft hooks are stopped and the pin removed from adjacent the 30 tail hook, the free turning tail hook permits the two strand groups to twist together as described above.

The tail hook is adjustable as to distance from the head hook but does not move forward during the twisting operation as is the case with banding machines according to the prior art with which I am familiar. The twisting of the elastic yarn causes an increased tension on the strands, since the tail hook does not move forward, thus preventing kinking until the proper twist is inserted in the strands. This automatically controls and 40 gives the proper twist to a given length of strands to be twisted, thereby insuring a more uniform percent of stretch and tension in the completed belt when it is on the pulleys of the machine on which it is used.

Other objects and advantages of the present invention 45 will become more apparent from the following detailed description taken in conjunction with the attached drawings in which:

Fig. 1 is a view showing an initial step in making a hook type band on a preferred form of apparatus according to the teaching of the present invention;

Fig. 2 is a view similar to Fig. 1 showing a subsequent step wherein two strand groups have been formed preparatory to twisting;

Fig. 3 is a view similar to Fig. 1 showing another subsequent step wherein the strand groups of Fig. 2 have been twisted and have twisted together upon themselves to form an elongated band; and

Fig. 4 is a view similar to Fig. 1 showing the completion of the hook type band preparatory to removing it from the apparatus.

Referring to the drawings, it is seen that apparatus in accordance with the teaching of the present invention includes what can be described as a head assembly, designated generally by the reference numeral 1, and what 55 can be described as a tail assembly, indicated generally by the reference numeral 2. The head assembly includes a pair of similarly shaped adjacent shaft members 3 and 4 each supported for rotation by a suitable frame 5. Each shaft member is provided with a pulley member 6 and a belt 7 is trained around the pulley members so that shaft members 3 and 4 may be rotated at the same speed and in the same direction.

Each shaft member has a hook extending in an axial direction from the end of the shaft member as shown in the drawing. Thus, hook 8 is shown as extending from shaft member 3 and hook 9 is shown as extending from shaft member 4. Shaft member 4 is provided with a spring clip 10 for holding an end of a length of yarn while the hook members are being threaded as described more fully hereinafter.

The tail assembly 2 includes a hook 11 which is supported by a bearing member 12 so that hook 11 may turn freely about a longitudinal axis indicated by the line A—A in Fig. 1. This longitudinal axis is preferably so located that an extension of line A—A toward the head assembly 1 will pass substantially midway between shaft members 3 and 4. With this positioning of hook 11 and since hook members 8 and 9 are similarly shaped and in adjacent relation as shown in the drawing, the respective hook members may be said to be located at the corners of an elongated isosceles triangle.

A pin member 13 is located adjacent hook 11 as shown in Figs. 1 and 2. This pin member is supported by suitable means, not shown, so that it may be readily removed from the location shown in Figs. 1 and 2, the support means also permitting the pin member to be moved along axis A—A if desired.

In practising a preferred method according to the teaching of the present invention, a length of yarn 14, which may be described as being strand material, is drawn from a suitable source such as a creel, not shown, located adjacent the head assembly 1. The yarn may be of any suitable material, even sufficiently flexible and strong non-metallic material, depending upon the properties desired in the finished band. Generally the yarn will be an elastic yarn, elastic nylon or cotton yarn for example, so that the completed band will be elastic in nature.

Preparatory to drawing the length of yarn 14 from a creel or the like, the free end X of the yarn is secured beneath spring clip 10 as shown in Fig. 1. The yarn is then drawn from the supply source and passed or threaded about tail hook 11, then about head hook 8, then back around tail hook 11 to head hook 9 as shown in Fig. 1, care being exercised not to stretch the elastic yarn unduly so as to decrease its elasticity. This completes what can be described as one threading cycle and, in each subsequent cycle, the yarn goes from head hook 9 to head hook 8 via tail hook 11, and back from head hook 8 to head hook 9 via tail hook 11.

The number of threading cycles employed depends, of course, upon the desired diameter for the completed band or belt. When the threading cycles are completed, there will be two groups of strands disposed in an elongated V as shown in Fig. 2. Thus, strand group 15 extends from tail hook 11 to head hook 8 while strand group 16 extends from the tail hook to head hook 9. It is apparent that the number of strands in each strand group can be predetermined as desired.

When the desired number of strands have been threaded on the hooks as just described, the length of yarn is cut to provide a cut end Y shown in Fig. 2. Yarn end X is then removed from beneath spring clip 10 and the two ends X and Y inserted among the strands of strand group 16 adjacent head hook 9. Once they are so inserted, the ends X and Y are preferably maintained within strand group 16 by holding the strand group by hand, where they have been inserted, preparatory to the twisting step next described.

With the yarn ends X and Y in proper position as just described and with pin member 13 in position adjacent tail hook 11 so that it extends between the strand groups 15 and 16 closely adjacent the tail hook, shaft members 3 and 4 are both rotated at the same speed and in the same direction as indicated by the curved arrows B shown in Fig. 2, thus causing head hooks 8 and 9 to rotate in the same direction and at the same speed. This action twists both strand groups 15 and 16 since pin member

13 forms an obstruction which holds tail hook 11 against rotation. Assuming that the yarn ends X and Y have been held in among the strands of strand group 16 by hand, they will be held until the twist locks them in the twisted strands of strand group 16. The twisting of both strand groups continues until the desired amount of twist is imparted to each strand group, twisting being stopped before kinking takes place. The configuration of strand groups 15 and 16 following the twisting just described may be observed in the portions of the strand groups shown adjacent head hooks 8 and 9 in Fig. 3.

When the desired amount of twist has been imparted to each strand group the rotation of the head hooks is stopped and pin member 13 is removed from between the twisted strand groups. This frees tail hook 11 for rotation whereby, due to the twist imparted to each strand group, the strand groups 15 and 16 twist themselves together as shown in Fig. 3. The curved arrow C shown in Fig. 3 indicates the direction of rotation of tail hook 11 showing, of course, that the twisted strand groups 15 and 16 twist themselves together in the direction in which the twist was imparted to them.

After the strand groups 15 and 16 have twisted together to adjacent the head hooks 8 and 9 as shown in Fig. 3, an open band hook 17 is inserted into the loop 18 which is on head hook 8. Loop 18 is then lifted off of hook 8 by lifting band hook 17 and sufficient tension is maintained on strand group 15 to prevent kinking while this is being performed. Then, the band hook and loop are brought over to the other head hook 9. The two strand groups 15 and 16 continue to twist together as the loop 18 is brought over to the other head hook 9 until the loop 18 and the loop 19 at the end of strand group 16 come together. Portion 20 of band hook 17, this being the portion which is already inserted through loop 18, is then also inserted through loop 19 which is on head hook 9. When this is accomplished, loop 19 is lifted off of head hook 9 by lifting band hook 17 and the portion 21 of the band hook is caught on head hook 9 as shown in Fig. 4. Then, by suitable clamping means indicated at 22 in Fig. 4, plier jaws for example, the portion 20 of the band hook is closed to grip the loops 18 and 19 together firmly. The band 23 may then be removed from head hook 9 and tail hook 11 and is ready for use. In such use, and after the band has been inserted through a pulley or the like, the band hook portion 21 will be passed through the loop 24 at the other end of the band and closed to form an endless band or round belt.

In an alternate method, following the forming of the two twisted strand groups as described above, the pin member 13 is moved toward the open end of the V instead of being removed completely from between the twisted strand groups as described above and the head hooks 8 and 9 continue to rotate to restore twist used up as the twisted strand groups twist together upon themselves behind the pin member. The pin member is preferably moved to the left along axis A—A as viewed in Figs. 1 and 2, and it is apparent that as it is moved away from the apex of the V, the tail hook 11 will start to rotate due to the twist present in the two twisted strand groups 15 and 16. The continued rotation of head hooks 8 and 9 is preferably at a speed proportional to the rate of movement of pin member 13 so that the twisting together of the strand groups and the restoring of twist by the head hooks will be substantially uniform. This alternate procedure has the advantage of producing a firmer band since the continuing twist imparted by head hooks 8 and 9 restores twist which is used while the two twisted strand groups 15 and 16 twist themselves together behind the pin member.

It is seen from the foregoing that I have described and illustrated methods and apparatus for making bands from strand material, such as nylon or cotton yarn, for example. By employing my apparatus and practising my methods, a band, or round belt as it can be called, can

be made in which any tendency of the completed band to untwist is counteracted by the twist which is present in the individual groups of strands. By burying the ends of the length of yarn used to make the band within one strand group prior to twisting, I eliminate knots or other intermediate fastening means and thus the completed band does not have undesirable bulges or kinks caused by the presence of a knot formed by tying the yarn ends together. Also, burying the ends of the length of yarn as described provides a much faster operation as compared to one involving forming a knot or otherwise attempting to secure the yarn ends to each other. In short, the completed band is in structural equilibrium, even though formed by twisting, presents a firm and smooth outer appearance, and has a controlled twist and percent of stretch.

While I have described and illustrated embodiments of my invention I wish it to be understood that I do not intend to be restricted solely thereto but that I do intend to cover all modifications thereof which would be apparent to one skilled in the art and which come within the spirit and scope of my invention.

What I claim as my invention is:

1. The method of making an elastic band of controlled stretch and twist which is useful for power transmitting purposes, said method comprising the steps of winding a length of elastic yarn into two groups of strands forming an elongated V, burying each end of said length of yarn in a strand group, placing an obstruction between said strand groups closely adjacent the apex of said V, said obstruction preventing rotation of said apex, twisting each end of said V in the same direction while maintaining said obstruction in place between said strand groups closely adjacent to the apex of said V to prevent rotation of said apex despite such twisting, preventing said apex from moving toward the ends of said V while said twisting occurs, stopping said twisting before kinking occurs, then, while continuing to hold the ends and apex of said V, moving said obstruction away from said apex toward the open end of said V, allowing the held apex to rotate as said obstruction is moved away from said apex to permit the twisted strand groups to twist together upon themselves, continuing to twist the ends

of said V in the same direction, at a speed proportional to the rate at which said obstruction is moved away from said apex to thereby control the twisting together of the strand groups behind the obstruction and to restore twist used up when the twisted strand groups twist together upon themselves, and then, when the twisted strand groups have twisted together upon themselves to form an elongated band, securing said ends of said V to each other.

2. The method of making an elastic band of controlled stretch and twist which is useful for power transmitting purposes, said method comprising the steps of temporarily securing the free end of a length of elastic yarn upon a first support, extending the length of yarn from said first support to a third support via a second support and then back from said third support to said first support via said second support, said second support being freely rotatable at a fixed position, continuing to thread said length of yarn in the manner described to form two strand groups of predetermined size having a common apex at said second support, cutting said length of yarn, removing the free end of the length of yarn from the temporary securing means on said first support and burying said free end and said cut end of yarn among the strands of the strand group extending from the first support to the second support, rotating said first support and said third support in the same direction while holding said second support stationary to produce two twisted strand groups, releasing said second support after a predetermined twisting of said strand groups has occurred to permit the twisted strand groups to twist together upon themselves to form an elongated band, and then securing together the ends of the twisted strand groups engaged by said first and third supports.
